Specification of Letters Patent. Patented Jan. 25, 1921.

Application filed October 28, 1916. Serial No. 128,322.

To all whom it may concern:

Be it known that we, HARRY B. WIER and WILLIAM H. CAPEN, citizens of the United States, residing at Plainfield, in the county of Union and State of New Jersey, and at New York, in the county of New York and State of New York, respectively, have invented certain new and useful Improvements in Telephones, of which the following is

10 a full, clear, concise, and exact description.

This invention relates to a speech-recording and reproducing device of the type known in the art as the "telephophone."

It is an object of the present invention to 15 generally improve the construction and efficiency of a device of this character and to adapt it for use in telephone exchange systems for the purpose of reproducing spoken telephone numbers in accordance with the 20 set position of a manually operable device. In order to accomplish this function, it is necessary to provide a plurality of recording and reproducing paths upon each of which a single number is recorded, so that when the 25 circuit of the reproducing magnet individual to such path is extended to a telephone, the number recorded on such path will be repeated.

The particular circuit arrangement which 30 may be employed for this purpose forms no part of the present invention, and hence will not be disclosed or described herein.

It has been found by experiment that when 35 recording and reproducing coils of the ordinary construction are used, there is a tendency for the magnetic record produced thereby on the magnetic recording medium to creep, which tends to reduce the permanency and quality of the record. In accordance with a feature of the present invention, this tendency is reduced by an improved construction of the core of the recording and reproducing coils, which provides a plurality of pole pieces, preferably three in number. 40 The core is thus substantially E-shaped and the magnetizing coil itself is placed upon the middle pole-piece, which becomes the active pole-piece. Also, in accordance with this feature of the invention, the projecting 45 end of the active pole-piece is beveled to present a fine edge to improve the quality of the record, whereas the outside pole-pieces are provided with flat faces substantially parallel to the surface of the recording me-

dium, in order that the reluctance of the 55 magnetic circuit may be a minimum.

Other features of the invention relate to the method of mounting the erasing coils, the provision of adjustments for the recording and reproducing coils and the erasing 60 coils, and the means employed for producing a record and for erasing the record preparatory to the production of a new record.

These and other features of the invention will more clearly appear from a consideration of the detailed specification and the accompanying drawings in which—

Figure 1 is a front elevation of the device as a whole;

Fig. 2 is an end view taken on the line 2—2 of Fig. 1;

Figs. 3 and 4 are enlarged views of a recording and reproducing coil and its support;

Figs. 5 and 6 are similar views of an erasing coil;

Fig. 7 is a diagram of the circuit employed in recording and reproducing a record; and

Fig. 8 is a diagram of the circuit employed for erasing a record.

80

The device as a whole is mounted upon a base 1 upon which are supported a plurality of standards 2. The upper ends of such standards are provided with bearings 3 which serve to support a shaft 4, upon which 85 shaft are mounted recording disks 5. These disks are of steel, are mounted in pairs on either side of the spacing members 6 and are held between such spacing members and a pair of collars 7. Each pair of disks is 90 further clamped together by means of suitable rivets 8, which construction prevents warping of the disks. Mounted on each of the supports 2 are segments 9, all of which may be of identical construction and one of 95 which is shown more in detail in Fig. 2. These segments are supported on the standards 2 by means of suitable arms 10. The shaft carries at one end a pulley 11, which is adapted to be driven through a belt 12 100 from a motor 13. Mounted in slots 14 on the segments 9 are a plurality of recording and reproducing coils 15, shown in detail in Figs. 3 and 4. As shown in Fig. 2, the various slots 14 are concentric, and during 105 the movement of the disks the recording coils travel over concentric circular paths on such disks.

Referring now to Figs. 3 and 4, the recording and reproducing coils are supported on the segments 9 by means of a projecting lug or bracket indicated at 65. Secured to 5 such bracket by means of screws 16, are a pair of lugs 17, which are adapted to fit in the slots 14, as more clearly indicated in Fig. 2, and serve to prevent rotation of such bracket about the thumb-screw 18, the shank 10 of which passes through the slot 14 and into the standard 65. By loosening the thumb-screw 18, the standard can be adjusted along the length of the slot. Pivoted to the standard by means of the screws 19, is a lever 20, 15 to the outer end of which the reproducing coil 15 is detachably secured. The outer end of the lever 20 is bifurcated, forming a lower portion 21 and an upper portion 22, between which an extension of the core 23 of 20 the reproducing and recording coil is adapted to be engaged. As is more clearly shown in Fig. 4 the core piece 23 of the recording and reproducing coil is in the form of a flat substantially E-shaped piece of silicon steel, 25 the coil being placed upon the middle projection 25 of the E. As is clearly shown in Fig. 3, the outer end of the lever 20 is inclined to the plane of the recording disk, and the outer end of the middle branch 25 of the 30 pole-piece, which passes through the recording and reproducing coil, is brought to a sharp edge by means of a bevel which is substantially perpendicular to the plane of the recording disk. The two outer branches of 35 the pole-piece, however, are beveled in the opposite direction so as to present a surface which is substantially parallel to the plane of the recording disk. The pole-piece 23 is provided with a pair of studs indicated at 40 24, which are adapted to pass under and to be held by a pair of springs indicated at 55, one end of such springs being attached to the lever 20 and the other end being provided with a cup-shaped portion adapted to 45 engage the head of the stud 24. By virtue of this construction it is possible to attach the pole-piece and recording coil carried thereby to the arm 20 by merely slipping the pole-piece into the bifurcation in the end of 50 the lever 20 with the studs 24 engaging the cup-shaped ends of the spring 55. The spring indicated at 56 is mounted on the bracket 65 with its free end bearing against the lever 20, tending to rotate such lever 55 about its pivot and to maintain the projecting pole-piece of the recording coil in yielding contact with the recording disks.

The erasing coils 26 are also mounted on the segment 9 and are positioned so as to 60 follow the same concentric paths, on the steel disks as are followed by the recording and reproducing coils 15. These erasing coils are wound upon a substantially flat core 41, the outer end of which is beveled in 65 order to present a sharp edge to the surface

of the disk 5. The core is supported on a lever 27, the outer inclined end of which is provided with a bifurcated portion, providing a slot between the portions 28 and 29, in which the inner end of the pole-piece 41 is 70 adapted to be inserted. The pole-piece 41 also carries a pair of studs 30 which are adapted to be engaged by the cup-shaped ends of a pair of retaining springs 31, which are mounted on the lever 27. The lever 27 is 75 pivoted at 32 on a bracket 33, which bracket passes through a slot 34 in the supporting segment 9. The bracket 33 is secured to a shaft 35 which is rotatably mounted in bearings 36 secured to the segment 9. The upper end of the shaft 35 is provided with a small hand wheel 37 by means of which the bracket 33 and the parts carried thereby may be rotated away from the disks 5. The bracket 33 is provided with a plurality of 80 depressions 38 and 39 with which the end of a retaining spring 40 is adapted to coöperate to hold the lever 33 in one of two positions. To the bracket 33 is attached one end of a spring 42, the other end of which bears upon 85 one end of the lever 27 and tends to hold the end of the erasing coil core in yielding engagement with the disk 5. The movement of the lever 27 about its pivot under the influence of spring 42 is limited by a suitable 90 pin or stop 54. It will be observed that the outer end of the lever 27 is inclined to the plane of the disk 5 so that the pole-piece of the erasing coil 26 is also inclined to the plane of the disk 5. The inclined mounting 100 of the pole-pieces of the recording and reproducing coils and the erasing coil is for the purpose of reducing friction.

As shown more clearly in Fig. 2, there are two sets of recording and reproducing coils 105 and a single set of erasing coils, providing two reproducing and recording coils for each recording path on the disk, the object of this arrangement being to permit the simultaneous recording of numbers at two 110 different points in the same recording path. While the numbers are being recorded and reproduced, the erasing coils are rotated away from the disks by means of the hand wheels 37.

In preparing the record for the particular apparatus for which the device is adapted to be used, the circuit arrangement indicated in Fig. 7 is employed. The record impressed upon each recording path consists of a single number such as 1, 2 or 3, etc., reproduced throughout the entire recording path. In order that these numbers when recorded shall be properly spaced for reproducing, and shall not overlap, a commutator indicated at 49 is provided, this commutator being driven by means of gears 43 from the shaft 4. A plurality of brushes indicated at 45 engage with the commutator and pilot lamps, adapted to be illuminated 115 120 125 130

through such commutator when various portions of the disk are positioned underneath the recording and reproducing coils, serve to indicate to the person making the record 5 when the number should be spoken.

As the same number is to be repeated a number of times in the same recording path, it is of advantage to simultaneously record such number on a plurality of points in the 10 same recording path on the disks. In the particular embodiment of the invention disclosed, this is accomplished by using two recording and reproducing coils which are spaced approximately 180 degrees from one 15 another on the circular recording path, and which are adapted to be connected in series with a telephone transmitter. As shown in Fig. 7, when the double pole switch 50 is thrown to the right, the two recording and 20 reproducing coils are connected in series in a circuit including a source of potential 44, a telephone transmitter 51, an inductance 46 and a capacity 47. Thus when the number to be recorded is spoken in the transmitter 25 51, the recording and reproducing coils 15 act to locally magnetize portions of the recording disk 5 at points 180 degrees apart. When it is desired to reproduce the numbers thus recorded, switch 50 is thrown to 30 the left, thus connecting the recording and reproducing coils with the telephone receiver 48. In actual practice when the device is employed in a telephone system, the recording and reproducing coils are connected 35 through various instrumentalities with the telephone receiver of an operator and the various recording and reproducing coils are successively connected to the receiver of such operator in order to repeat 40 several digits of a number. For example, in order to repeat the numbers 1-2-3-4, the recording and reproducing coils individual to the path on the disk upon which the number 1 was recorded, will first be switched 45 in, and then the recording and reproducing coils upon which the numbers 2-3-4 have been recorded, will be successively switched in.

As the records produced on the disks are 50 not of a permanent nature, it is necessary at definite intervals to erase such records and to impress new records thereon. This erasing is accomplished by means of the erasing coils, previously described, which 55 are adjusted in proximity with the disks and connected in the circuit arrangement shown in Fig. 8. When the switch indicated at 53 is thrown to the left, current is sent through the erasing coil 26 from a source of 60 potential indicated at 52. This current is of sufficient value to raise the steel of the disk to the saturation point in the path of the particular erasing coil employed. This current is maintained during several revolutions 65 of the disk, and then the switch 53 is

thrown to the right, reversing the current and reducing the current to such a value that the steel is practically demagnetized, and any record or extraneous noise on the disk is erased. If necessary, the current 70 can be still further reduced by means of the variable resistance indicated at 52.

What is claimed is:

1. In a telegraphophone, a magnetic recording medium, a recording and reproducing coil 75 pivotally movable relative thereto, and a magnetic core provided with an active pole piece and a plurality of inactive pole-pieces, said active pole-piece engaging said recording medium and serving to support such recording and reproducing coil and said inactive pole pieces being spaced from said recording medium. 80

2. In a telegraphophone, a magnetic recording medium having a smooth surface, a recording and reproducing coil associated with said recording medium, and a substantially E-shaped core upon the center branch of which such coil is mounted, said center branch only having contact with said recording medium. 85

3. A telegraphophone comprising a rotatable magnetic disk and a plurality of recording and reproducing coils mounted at different radial distances from the center of rotation 95 of said disk, whereby a plurality of independent records may be impressed on said disk in a plurality of concentric circular paths. 90

4. A telegraphophone comprising a rotatable 100 magnetic disk and a plurality of recording and reproducing coils mounted at different radial distances from the center of said disk, and means for independently adjusting said coils in the circular paths about the center 105 of rotation of said disk.

5. A telegraphophone comprising a rotatable magnetic disk, a plurality of recording and reproducing coils adapted to be included in a single recording and reproducing circuit, and 110 means for positioning said coils in angular spaced relation at equal radial distances from the center of rotation of the disk, whereby a plurality of identical records may be simultaneously produced in a single recording path on the disk. 115

6. A telegraphophone comprising a movable recording medium, recording and reproducing coils for producing a record on said recording medium, an erasing coil positioned 120 adjacent such recording medium, and a support for said erasing coil adapted to support the same in operative and inoperative positions.

7. A telegraphophone comprising a recording 125 medium, reproducing and recording coils, an erasing coil movable relative to said reproducing and recording coils, magnetic cores for said erasing coil pivotally mounted supports for said coils, and springs engag- 130

ing one end of such supports to maintain such cores in yielding contact with the recording medium.

8. In a telephone, a magnetic recording medium having a smooth recording surface, a recording and reproducing coil movable relative thereto, a magnetic core for such coil, and a plurality of pole pieces forming a part of such core upon one of which pole

pieces said coil is mounted, the latter pole ¹⁰ piece only being engaged with said recording medium.

In witness whereof we hereunto subscribe our names this 27th day of October, A. D. 1916.

HARRY B. WIER.
WILLIAM H. CAPEN.
